UNITED STATES PATENT OFFICE

CHARLES E. LOEHR, OF WOOSTER, OHIO, AND OSCAR MACNAB, OF EVANSTON, AND WILLIE R. CHAMBERLIN, OF CHICAGO, ILLINOIS, ASSIGNORS TO WOOSTER PRODUCTS INC., OF WOOSTER, OHIO, A CORPORATION OF OHIO

TRIM FOR WALL COVERINGS

Application filed December 16, 1931, Serial No. 581,356.

The invention relates to trim members for wall coverings and the like, and more particularly to metal trim members of solid cross section adapted for use with flexible

covering in position and at the same time presenting a pleasing and ornamental appearance.

5 In the past, metal trim members for similar purposes have included an edge-abutting member and a securing flange, and have been

member which will provide a pleasing and ornamental appearance when installed without requiring a finishing operation before or after installation.

10 10 been found unsatisfactory for several reasons.

A serious objection to these sheet metal members is that they do not possess sufficient rigidity to maintain their shape before 15 or after installation, and after installation the exposed portions of the members are relatively easily dented or bent out of shape, resulting in an unsightly appearance.

Another objection to these sheet metal 20 members is that they require a finishing operation such as painting or polishing, which operation cannot be satisfactorily done before installation because the finish is apt to become damaged during installation. On the 25 other hand, if the trim members are finished after installation, the flexible covering inserted therein is very likely to be damaged during the finishing operation.

Another difficulty results from the fact 30 that the securing flanges of the sheet metal members are of uniform thickness, and form an offset with the undersurface to which they are secured. This offset causes a corresponding shoulder in the surface of the 35 covering, requiring building up to the covering adjacent the trim member, or cutting away or rabbeting the inner surface of the covering or the undersurface to which the trim member is secured, in order to provide 40 a smooth exterior on the covering.

Accordingly, it is an object of the present invention to provide a metal trim member of solid cross section for wall coverings and the like, having an improved securing flange 45 which will avoid the necessity for building up to the covering or rabbeting the wall or covering.

Another object is to provide a trim member having an edge-abutting and overlapping portion for gripping and maintaining the

60 These and other objects are accomplished by the improvements comprising the present invention, which may be stated in general terms as consisting preferably of an extruded metal trim member of solid cross section having an edge-abutting and overlapping portion and a securing flange extending angularly therefrom, the securing flange tapering 65 from a maximum thickness at the edge-abutting portion to a minimum thickness at its free edge.

Preferred embodiments of the present improvements are illustrated in the accompanying drawing, in which

Figure 1 is a perspective view of a portion of a room provided with a flexible wall covering, showing the relative positions of 75 the improved trim members;

Fig. 2 is an enlarged fragmentary sectional view through an outside corner of the room, as on line 2-2, Fig. 1;

Fig. 3 is an enlarged fragmentary sectional view through an inside corner, as on line 3-3, Fig. 1; and

Fig. 4 is an enlarged fragmentary sectional view through the outside edge of the door, as on line 4-4. 85

Similar numerals refer to similar parts throughout the several views.

The walls of a room are indicated at 10, 11 and 12, and the wall 11 is provided with a door opening 13. A door 14 is hung in 90 the opening 13 in the usual manner, and the walls are provided at their bottom edges with a suitable baseboard 15.

As shown in Fig. 1, the walls are covered with a flexible covering 16, such as linoleum, 95 which extends from the baseboard 15 upwardly part way to the ceiling of the room. At the outside corner of walls 11 and 12 a trim member 17 is provided for abutting and overlapping the adjacent edges of the 100

coverings on walls 11 and 12, and at the inside corner between walls 10 and 11, a trim member 18 is provided for abutting and overlapping the adjacent edges of the coverings on walls 10 and 11.

5 Suitable trim members 19 and 20 are provided, respectively, at the upper edges of the covering 16 on all the walls, and at the outside faces of the door jambs 14.

10 Each of the improved trim members is preferably of solid cross section and may be of extruded brass or aluminum and the like.

The trim member 17, shown in cross section in Fig. 2, includes a pair of intersecting flanges 21a, angularly disposed to each other to form substantially a V in cross section. An edge-abutting portion 22a extends outwardly from the apex of the V, and is provided with angularly disposed surfaces 23a which are adapted to abut the adjacent edges of the coverings 16 on walls 11 and 12.

15 Each securing flange 21a tapers from a maximum thickness at the apex of the V, or at the edge-abutting portion 22a, to a minimum thickness at its free edge, so that the free edge is substantially sharp. The undersurface of each flange 21a is adapted to lie in the plane of the abutting wall surface, so that the upper surface of the flange inclines from a maximum thickness at the adjacent edge-abutting surface to a minimum thickness at its free edge, and a series of countersunk holes are provided in the flange 21a for attachment to the abutting wall, as by screws 24.

20 The particular construction of the securing flanges 21a avoids the formation of a corresponding shoulder in the surface of the covering 16, eliminating the necessity of building up to the covering at the edge of the securing flange, or rabbeting the wall or covering.

An edge-overlapping flange 25a preferably extends angularly from the edge-abutting portion 22a adjacent each surface 23a, and the undersurface 26a of each flange 25a is substantially parallel with the outer surface 27a of the corresponding flange 21a, and spaced therefrom a distance corresponding to the thickness of the covering 16. The flanges 25a are adapted to overlap and substantially grip the adjacent edges of the covering 16 on walls 11 and 12, so as to conceal those edges and aid in maintaining the coverings in position.

25 The trim member 18, which is provided at the inside corner between walls 10 and 11, is shown in cross section in Fig. 3, and includes a pair of intersecting securing flanges 21b. The flanges 21b are angularly disposed to each other to form substantially a V in cross section, and the inner surfaces of the flanges are adapted to lie in the plane of the surfaces of the walls 10 and 11 respectively.

An edge-abutting portion 22b extends inwardly from the apex of the V, and is adapted to be located in the corner between the walls 10 and 11. The edge-abutting portion 22b is provided with angularly disposed edge-abutting surfaces 23b which are adapted to abut the adjacent edges of the coverings 16 on walls 10 and 11.

30 Each securing flange 21b tapers from a maximum thickness at the edge-abutting portion 22b to a minimum thickness at its free edge, and is provided with a series of holes for attachment to the walls 10 and 11 respectively as by screws 24.

The edge-abutting portion 22b is provided with a portion 28 extending angularly inward from the portion 22b away from the apex of the V, and at an angle to the securing flanges 21b. The portion 28 is preferably provided with angularly projecting edge-overlapping portions 25b which overlap and substantially grip the adjacent edges of the coverings 16 on walls 10 and 11. The undersurface 26b of each portion 25b is substantially parallel with the outer surface 27b of the corresponding flange 21b, and is preferably spaced therefrom a distance corresponding to the thickness of the floor covering 16.

35 It is sometimes desirable to cover doors with a flexible covering such as linoleum. The door 14 in Fig. 1 is provided with a covering 16', the forward edge portions of which are secured by a trim member 29, and the other edges are secured by suitable trim members 30.

The trim member 29 is shown in cross section in Fig. 4, and includes securing flanges 21c, disposed in parallel relation to each other and located one on the front face and one on the rear face of the door. The inner surfaces of the flanges 21c are adapted to lie in the planes of the front and rear faces of the door, respectively.

40 The trim member 29 preferably includes a covering edge-abutting portion 31, which is located around forward edge 32 of the door and extends between the flanges 21c.

The portion 31 is provided with an edge-abutting surface 23c adjacent each securing flange 21c, which surfaces are adapted to abut the forward edges of the covering 16' on the front and rear faces respectively of the door 14.

45 Each securing flange 21c tapers from a maximum thickness at the edge-abutting portion 31 to a minimum thickness at its free edge, and is provided with a series of holes for attachment with the door 14, as by screws 24.

50 Adjacent each edge-abutting surface 23c, the edge-abutting portion 31 is provided with an edge-overlapping flange 25c projecting angularly therefrom, and the flanges 25c are adapted to overlap and substantially 130

grip the coverings 16' on the front and rear faces of the door.

The under surface 26c of each flange 25c is substantially parallel with the outer surface 27c of the corresponding securing flange 21c, and is preferably spaced therefrom a distance corresponding to the thickness of the covering 16'.

Each of the improved trim members above 10 described is of solid cross section and all of the walls thereof have sufficient thickness, so that the members possess relatively great rigidity and durability. Consequently, the improved trim members will maintain their 15 shape before installation, and after installation the exposed portions thereof will offer relatively great resistance to denting or marring of their appearance.

The extruding metal trim members 20 possess an attractive finished appearance which is sufficiently durable so as not to be marred during installation.

In applying a flexible wall covering to a room, the improved trim members are first 25 secured at their proper relative locations by means of the screws 24 passing through the respective securing flanges. The covering is then cut to proper sizes to fit in the panels bordered by the trim members. Then the 30 covering is applied and made to adhere to the wall and the outer surfaces of the securing flanges of the trim members by means of a suitable adhesive such as glue. The flexibility of the covering is sufficient to permit 35 insertion of the edge portions of the covering under the edge-overlapping portions of the trim members.

The improved trim members each include 40 securing flanges which are tapered to a substantially sharp edge at their free edge portion, so that the marginal edges of the wall covering or linoleum lay over the securing flanges without causing a shoulder in the covering because of an offset at the edge of 45 the securing flange. Accordingly, it is not necessary to build up to the covering at the edge of the securing flanges, nor to rabbet either the surface of the wall or the under-surface of the covering.

50 Each of the improved trim members includes overlapping flange portions which are spaced from the corresponding securing flanges a distance corresponding to the thickness of the covering. Consequently, the 55 edges of the wall coverings are concealed to enhance the appearance of the finished wall, and the overlapping flanges securely grip or hold the edge of the covering so as to aid in maintaining the covering in position upon 60 the wall.

The finished room is thus provided with 65 practical and durable trim members which not only securely hold and conceal the marginal edges of the covering, but also present a pleasing and ornamental appearance.

We claim:

1. A trim member for wall coverings and the like including, a plurality of angularly disposed securing flanges, the trim member being provided with an edge-abutting surface adjacent each securing flange, and an edge-overlapping portion extending angularly from each edge-abutting surface, each securing flange having its underside surface in the plane of the wall and its upper surface inclined from a maximum thickness at the adjacent edge abutting surface to a minimum thickness at its free edge, and each edge-overlapping portion having its underside surface substantially parallel to the upper 70 surface of the adjacent securing flange. 75

2. A trim member for wall coverings and the like including, an edge-abutting portion provided with edge-abutting surfaces, a plurality of securing flanges each extending angularly from the edge-abutting portion, each securing flange having its underside surface in the plane of the wall and its upper surface inclined from a maximum thickness at the edge-abutting portion to a minimum thickness at its free edge, an edge overlapping portion extending angularly from the edge-abutting portion adjacent each edge-abutting surface, and each edge overlapping portion having its underside surface substantially parallel to the upper 80 surface of the adjacent securing flange. 85

3. A metal trim member of solid cross section for wall coverings and the like including, intersecting securing flanges forming a 100 V in cross section, an edge-abutting member located at the apex of the V, the edge-abutting member being provided with angularly disposed edge-abutting surfaces, and an edge-overlapping portion extending angularly from the edge-abutting member at each edge-abutting surface, each securing flange having its underside surface in the plane of the wall and its upper surface inclined from a maximum thickness at the apex of the V 105 to a minimum thickness at its free edge, and each edge-overlapping portion having its underside surface substantially parallel to the upper surface of the adjacent securing flange. 110
